ENVELOPE OPENER

Sven Olof Ohlsson, Malmo, Sweden, assignor to
Aktiebolaget Addo, Malmo, Sweden, a corpora-
tion of Sweden

Application May 17, 1950, Serial No. 162,458
In Sweden May 23, 1949

4 Claims. (Cl. 30—265)

1

The known envelope openers function either in the same way as an ordinary paper knife or in such a way that a narrow marginal strip is completely severed from the envelope by means of one or more sharp cutting means. The first-mentioned type of envelope openers will tear the envelope into pieces and do not allow a rapid opening of a great number of envelopes, while the last-mentioned type of envelope openers have the disadvantage that the strips cut off make the desk untidy and easily clog the opener so that it cannot function in the intended manner until it has been cleaned.

The principal object of the present invention is to provide an envelope opener which does not present the above-mentioned disadvantages inherent in prior art openers. It is also an object of the invention to provide an envelope opener having very simple and cheap construction and which is extremely easy to operate.

Other objects of the invention will be clear from the following description of a preferred embodiment shown in the accompanying drawing. In the drawing:

Fig. 1 is a top view of the envelope opener according to the invention.

Fig. 2 shows, on a larger scale, the cutting means of the opener as well as the adjacent parts of the frame in horizontal projection.

Fig. 3 is a section on line III—III in Fig. 2.
Fig. 4 is a section on the line IV—IV of Fig. 2.

The illustrated envelope opener has a relatively heavy, elongated frame 1 provided with a longitudinal guide channel 2 for leading an envelope edge past a cutting means mounted on the frame by introducing the edge of the envelope into the slit 20 formed in the channel 2. This cutting means is mounted in a pocket 3 of the frame and consists of an abutment roller 4 having cylindrical periphery, and of a cutting roller 5.

In the embodiment shown the abutment roller is a ball bearing mounted on a pin 6. The roller 5 is also an ordinary ball bearing mounted on a pin 7, the outer race ring of the latter ball bearing being, however, ground so as to present a relatively sharp peripheral edge 8. Of course, the peripheral edge may also be formed as a separate ring secured to the exterior of the outer race ring of the ball bearing. The race ring carrying the peripheral edge 8 is, moreover, fixedly connected with a disk 9 projecting somewhat from the frame 1 out of the pocket 3, as will appear from Fig. 3, the periphery of the disk being knurled in order that it may be possible

2

easily to rotate the roller 5 by exerting a force upon the edge of the disk 9 with a finger. The greater part of the roller 5 is covered by a cap 10 attached to the pin 7 and having a pair of channel-shaped flaps 11 and 12 (Figs. 2 and 4) reaching downwardly into the pocket 3 adjacent the rollers 4 and 5. Flaps 11 and 12 are shaped to form continuations of guide channel 2 in the pocket 3. The pins 6 and 7 are so located that the peripheral, cylindrical surface of the abutment roller 4 projects into the space in pocket 3 between the flaps 11 and 12 while the peripheral edge 8 of the cutting roller 5 projects into the said space from the other side in immediate proximity to the peripheral surface of the roller 4 but without coming into contact therewith. The distance between the periphery of the roller 4 and the peripheral edge 8 should be chosen so as to approximately correspond to, or, preferably, be somewhat smaller than the material thickness of the paper wall of the thinnest envelope to be opened in the apparatus.

When an envelope is to be opened by means of the described apparatus an edge of the envelope is introduced into the guide channel 2 of the frame 1 to the right of the rollers 4 and 5 with respect to Fig. 1, whereafter the envelope is moved along the guide channel up to the nip of the rollers 4 and 5. Then the roller 5 is rotated with a finger by means of the disk 9 until the peripheral edge 8 of the roller 5 and the roller 4 grasp the envelope edge, whereafter it is possible easily to draw the envelope further along the guide channel 2 past the rollers 4 and 5 while attention is paid to the envelope edge bearing firmly against the bottom of the guide channel. While the envelope edge is moved through the nip of the rollers 4 and 5, the peripheral edge 8 breaks one side wall of the envelope adjacent the envelope edge in question, whereas the other side wall remains unbroken, because the peripheral edge 8 does not reach up to the smooth peripheral surface of the abutment roller 4. In this manner the envelope is opened without material being severed from it.

As will appear from Fig. 1, the frame 1 may be provided with two guiding rods 14 which are preferably of round cross section and are arranged above the guide channel 2 on each side thereof. It is possible to let one's fingers slide along these rods, while the envelope edge is moved through the guide channel 2 past the cutting means.

Of course, the invention must not be considered as limited to the embodiment described

above and shown in the drawing, for many modifications may be resorted to without departing from the scope of the invention.

What I claim and desire to secure by Letters Patent is:

1. A device for opening envelopes by slitting through one wall thereof comprising; a frame formed with a longitudinal guide channel to receive the edge of an envelope, a pocket formed in the frame intersecting the channel adjacent one end of the frame, parallel pins upstanding in the pocket on opposite sides of the axis of said channel, rollers on said pins having their peripheries spaced on opposite sides of the axis of the channel, the periphery of one roller being cylindrical and the periphery of the other roller being formed with projecting V-shaped cutting edge, a thumb-wheel integral with said other roller having its edge projecting from the side of said pocket, and guide rails extending along the frame above the channel and also above said rollers.

2. A device for opening envelopes by slitting through one wall thereof comprising; a frame formed with a longitudinal guide channel to receive the edge of an envelope, a pocket formed in the frame intersecting the channel adjacent one end of the frame, parallel pins upstanding in the pocket on opposite sides of the axis of said channel, rollers on said pins having their pe-

ripheries spaced on opposite sides of the axis of the channel, the periphery of one roller being cylindrical and the periphery of the other roller being formed with projecting V-shaped cutting edge, a thumb-wheel integral with said other roller having its edge projecting from the side of said pocket, and guide rails extending along the frame above the channel and also above said rollers.

3. An arrangement according to claim 1 wherein the said other roller is surrounded, except for the portion adjacent the said one roller, by a shield supported on the associated pin.

4. An arrangement according to claim 3 wherein the shield includes projecting flaps on opposite sides of the space between the rollers extending into the said pocket in alignment with said channel and shaped to form a continuation of said channel.
